UNITED STATES PATENT OFFICE.

KURT WIESINGER, OF ZURICH, SWITZERLAND.

HIGH-SPEED RAILWAY.

Application filed March 7, 1924. Serial No. 697,441.

To all whom it may concern:

Be it known that I, KURT WIESINGER, citizen of Germany, residing at Zurich-7, Switzerland, have invented new and useful 5 Improvements in High-Speed Railways, of which the following is a specification.

The high speed railways hitherto known are either railways with special track and superstructure, or standard railways. The 10 special railways have their own tracks after the manner of elevated railways, and the initial costs of these are considerable. The railways themselves are therefore wasteful, and they have not stood the test.

15 The standard railways with high speed use a reinforced superstructure of normal main lines, as, owing to the danger of derailment due to their high speed, their cars must be very heavy. Consequently the initial cost 20 of such railways with two rails, and particularly the cost of upkeep, is too high. Owing to their wastefulness they have not been able to be introduced.

The invention here described is intended 25 for the construction of a high speed railway with a maximum speed of about 100 m/s, or 360 km/h, employing normal rails and sleepers. The plant is that of a standard railway, on whose rails the cars are positively 30 guided, so that the danger of derailment is entirely eliminated, and the weight of the cars is reduced to a minimum by the right build of the same.

The invention is illustrated by Figs. 1 and 35 2. Fig. 1 is a lateral view of a train driven, for example, by a propeller; Fig. 2 is a transverse section.

The front car is designated by 1, the trailers by 2 and the rear car by 3. The 40 length of the train is determined by the number of trailers 2. All the cars are coupled so closely that at the coupling point there can be no interruption of the streamline current set up by the whole train.

45 The cars, which are suitably built for keeping the surface small with transverse section either round or flattened below, are mounted on springs opposite the axles 4, which each support two wheels 5 revolving 50 independently of each other. The wheel parts projecting from the side wall of the body 6 of the cars are enveloped in the lining 7 somewhat similar to the streamline, in order to reduce the atmospheric resistance 55 of these parts to a minimum as well. The wheels 5 engage with their high flanges un-

der the heads of the rails 8, which are inclined well inwards, so that the cars are positively kept on the rails.

In the case described above the driving 60 power is supplied, for example, by an airship motor 9 which actuates a slow-acting adjustable propeller. Of course any other kind of drive or power engine could be employed. At the front of the train there are 65 head-lights 10 for lighting the track, and windows 11 for observation purposes.

By means of the invention here described a high speed railway is created which even 70 at a speed of 100 m/s or 360 km/h is economical and therefore worthy of construction. By the automatic run of the cars the axle pressure can be reduced to 2000 or 3000 kg., as against the present 16000 to 20000 kg. in Europe and over 30000 kg. in America. 75 This is a point of great importance, as all the dynamic strains increase during the journey, in the first place with the moved weight and in the second with the square of speed. For the same strains on the superstructure the moved weight is therefore to be diminished with the square of the speed of travel. This can only be done in standard railways by special light constructions 80 (aluminium—and magnesium—or similar 85 alloys) if the cars are secured against derailment by their automatic run, and the engine output is reduced to a minimum with the least resistance to motion.

All these claims are fulfilled by the invention herein described. 90

I claim:

1. In a high-speed railway of the character set forth, in combination, a plurality of cars, closely interconnected with each other and individually so designed as to give the assembled train substantially the form of a streamline body, a track of rails, and sets of wheels supporting the cars, said rails and said wheels being inwardly inclined to 100 substantially the same degree toward the longitudinal axis of the car.

2. In a high-speed railway of the character set forth, in combination, a plurality of cars, adapted to be closely connected to 105 one another and individually so designed as to impart to the assembled train the form of a streamline body, a track of rails, and sets of wheels for the cars, said rails and said wheels inwardly converging toward the 110 longitudinal axis of the cars, and structural streamline members on said cars designed.

to shield the outwardly exposed parts of wheels being inwardly inclined to substantially the same degree toward the longitudinal axis of the cars, and flanges on said wheels adapted to have interlocking engagement with the inner sides of the railheads. ¹⁰

3. In a high-speed railway of the character set forth, in combination, a plurality of cars so designed and interconnected as to impart to the assembled train the form of a streamline body, a track of rails, sets of wheels for the cars, said rails and said

In testimony whereof I have signed my name to this specification.

KURT WIESINGER.
